CLAIM

The ornamental design for a phone with multi-position screen, as shown and described.

DESCRIPTION

FIG. 1 is a front view of a phone of the new design;

FIG. 2 illustrates a top view thereof;

FIG. 3 illustrates a right side view thereof;

FIG. 4 illustrates a left side view thereof;

FIG. 5 illustrates a bottom view thereof;

FIG. 6 illustrates a back view thereof;

FIG. 7 illustrates a right side view thereof, with the screen portion open;

FIG. 8 illustrates a front view thereof, with the screen portion open in a first position; and,

FIG. 9 illustrates a front view thereof, with the screen portion open in a second position.

The broken lines shown in the drawing that are immediately adjacent to the claimed surfaces and define unshaded regions represent the bounds of the claimed design, while all other broken lines, including all of the words, numbers, and characters are directed to environment and are for illustrative purposes only; the broken lines form no part of the claimed design.
